UNITED STATES PATENT OFFICE.

WALTER J. SPAULDING, OF SANTA BARBARA, CALIFORNIA.

GRADOMETER.

1,136,731.

Specification of Letters Patent.

Patented Apr. 20, 1915.

Application filed March 19, 1914. Serial No. 825,806.

To all whom it may concern:

Be it known that I, WALTER J. SPAULDING, a citizen of the United States, and a resident of Santa Barbara, in the county of 5 Santa Barbara and State of California, have invented a new and Improved Gradometer, of which the following is a full, clear, and exact description.

My invention relates to devices for measuring inclinations or grades with reference to a horizontal line, and has reference more particularly to devices for use in connection with automobiles, for indicating the grade of the road.

15 The object of the invention is to provide a simple and inexpensive gradometer which has few movable parts adapted to get out of order, and in which the movement of the movable parts is damped by the medium 20 in which the parts are adapted to move.

I attain the above object by a convenient structure illustrated in the accompanying drawings forming a part of the specification, in which similar characters of reference indicate corresponding parts in all the views 25 and wherein—

Figure 1 is a vertical section through an embodiment of my invention, the same being shown secured to the dashboard of a vehicle; 30 Fig. 2 is a front elevation of the same; and Fig. 3 is a section on line 3—3, Fig. 1.

Referring to the drawings, 4 represents a receptacle, which is preferably a sector of a cylinder having an inlet thereto at the central portion and which inlet to the receptacle is closed by a cap 5 adapted to be tightened to the receptacle by means of a nut 6 and whereby said receptacle is hermetically closed. A gasket 7 is preferably provided 35 in said cap 5 to perfectly seal the receptacle. The parallel sides 8 of the receptacle 4, which form the ends of the cylinder, are extended past one of the radial sides 9, as shown at 10, and the alining edges 11 of said 40 extensions are substantially parallel with the central line of the sector. Thus, when said edges 11 are brought against the vertical member 12, as shown in Fig. 1, the axis of the sector is also substantially vertical. Ad- 45 jacent the edges 11 the extensions 10 of the sides 8 are provided with means whereby the receptacle 4 is secured to the member 12.

50 A pendulum 13 is mounted to vibrate in the receptacle 4 with the axis of oscillation on the central line of the receptacle and adjacent the top thereof, i. e., at the narrow

part where the inlet to the receptacle is provided. The said axis is a pin 14 bearing in recesses 15 formed in the sides 8 and maintained in said sides in any suitable way. 60 Said pendulum 13 is in width equal substantially to the distance between the sides 8, a slight clearance 16 being left between the sides of the pendulum and the sides 8 of the receptacle. A similar clearance 17 is left 65 between the bottom of the receptacle and the lower end of the pendulum. Therefore, it may be said that the pendulum 13 divides the receptacle into two parts. A part of a gear wheel 18 is integral with the pendulum 70 13 adjacent its axis of oscillation, and which axis of oscillation is the axis of the gear. Meshing with the gear 18 is a pinion 19, the stub-shaft 20 of which projects through the radial side 9 forming the front of the device. 75 On this radial side a cylindrical casing 21 is provided, the axis of which casing is common with the axis of the stub-shaft 20. The projecting end of the stub-shaft 20 receives a hand 22 adapted to revolve when the pinion 19 revolves. A dial 23 is provided in the casing 21 and on which dial the grade is indicated by the displacement of the hand 22 caused by the displacement of the pendulum 13. A glass 24 is secured to the casing 21 to 80 protect the dial and the hand.

The reason for making the clearance 16 between the sides of the receptacle 4 and the pendulum is to increase the resistance to the displacement of the pendulum in the liquid 90 receptacle 4. That is to say, when there is a sudden displacement of the casing due to a change in grade, the pendulum will not be set into vibration, as the fluid passing from one side of the pendulum to the other side 95 of the pendulum is resisted in movement by the clearance 16 and 17. To make this resistance high, the receptacle 4 is preferably filled with oil shown at 25, and thus any vibration of the pendulum, due to a sudden 100 displacement of the casing, is obviated.

Having thus described my invention, I claim as new and desire to secure by Letters Patent:

In a gradometer, a casing having the shape 105 of a sector of a cylinder, said casing having an inlet at the narrower end; a cap for said casing engaging the inlet and closing said casing hermetically; a fluid in said casing; a pendulum mounted to vibrate in said casing 110 between the radial sides thereof, said pendulum having its width substantially equal to

the distance between the parallel sides of the casing, thus dividing said casing into two parts intercommunicating through the clearance formed by the pendulum and the parallel sides of the casing, whereby said fluid 5 dampens the vibration of the pendulum in said casing; a gear associated with the pendulum; a pin engaging the gear; a hand associated with the pinion; and a dial for said 10 hand, said hand being adapted to register

on the dial the displacement of the casing with reference to the pendulum.

In testimony whereof I have signed my name to this specification in the presence of two subscribing witnesses.

WALTER J. SPAULDING.
